UNITED STATES PATENT OFFICE

139,051

DESIGN FOR A BEAM ASSEMBLY FOR A
WEIGHING SCALE

Henry Dreyfuss, New York, N. Y., assignor to
Fairbanks, Morse & Co., Chicago, Ill., a corpora-
tion of Illinois

Application June 22, 1944, Serial No. 114,142

Term of patent 14 years

(Cl. D52—10)

To all whom it may concern:

Be it known that I, Henry Dreyfuss, a citizen
of the United States, residing at New York city,
in the county of New York and State of New
York, have invented a new, original, and orna-
mental Design for a Beam Assembly for a Weigh-
ing Scale, of which the following is a specifica-
tion, reference being had to the accompanying
drawing, forming part thereof.

In the drawing

Fig. 1 is a top plan view of a beam assembly
for a weighing scale, showing my new design;

Fig. 2 is a front elevational view thereof;

Fig. 3 is an elevational view of one end there-
of, and

Fig. 4 is an elevational view of the opposite end
thereof.

I claim:

The ornamental design for a beam assembly
for a weighing scale, as shown.

HENRY DREYFUSS.
